WILLIAM EDWIN NETTLE, PAUL SELBY, JAMES BLYTHE, AND JOSEPH HENRY HOLMAN, OF JOHANNESBURG, TRANSVAAL, SOUTH AFRICA.

RECIPROCATING ROCK-DRILL FOR SUPPLYING WATER TO THE BORE-HOLES DURING DRILLING.

1,360,011.

Specification of Letters Patent. Patented Nov. 23, 1920.

Application filed April 23, 1919. Serial No. 292,046.

To all whom it may concern:

Be it known that we, WILLIAM EDWIN NETTLE, a subject of the King of Great Britain, PAUL SELBY, a citizen of the United States, JAMES BLYTHE, a subject of the King of Great Britain, and JOSEPH HENRY HOLMAN, a subject of the King of Great Britain, all residents of Johannesburg, Transvaal Province, Union of South Africa, have invented certain new and useful Improvements Applicable to Reciprocating Rock-Drills for Supplying Water to the Bore-Holes During Drilling, of which the following is a specification.

15 This invention appertains to reciprocating rock drills (*i. e.*, those in which the piston, piston rod, chuck or tool holder and tool or bit are all rigidly connected and reciprocated together) and to means for 20 supplying water to the bore-holes as they are being formed by such machines.

In the specification of a prior application for patent filed by the present applicants on June 26, 1918, Serial No. 242,066, an arrangement is described in which the cylinder back cover of the machine and a fluid holding vessel or container are each constructed with a separate stuffing box and gland through which works the tube attached 30 to the reciprocated parts of the drill and which tube serves for conveying the water or other fluid from the aforesaid vessel or container to a passage or conduit leading through said reciprocated parts. The said 35 vessel or container was constructed integral with the cylinder back cover, and the part connecting them was appropriately constructed to form or provide a housing for the aforementioned stuffing boxes or glands.

40 With this arrangement it was necessary from time to time to tighten or adjust the glands by hand, and for that reason the part or housing inclosing them was formed with an opening or slot to allow of ready access 45 thereto.

Now the object of the present improvements is to obviate the necessity for the hand adjustment of the glands, and to provide simple and efficient means for effecting such 50 adjustment automatically, and one that is more compact, stronger and cheaper to construct. This admits of the glands being completely inclosed and so rendered inaccessible. The inclosing of the glands is desirable 55 as the drills or machines are often

operated by unskilled persons who are incapable of effecting proper adjustment, which leads to disorganization and breakage of the parts. A further object of the present invention is to design the packing parts 60 in such a way that they can be assembled or put together by a skilled person in a compact and convenient form for transport. It is preferred to construct the said parts in cylindrical or cartridge form and of such a 65 size that an operator can, if necessary carry one or more on his person and when requisite remove a worn one and replace it by a new one, with little loss of time. This obviates derangement of the parts in putting 70 the same in position and it enables the renewal to be effected by an unskilled person.

According to the present invention, in lieu of the two separate packing glands of the previous arrangement we provide what we 75 may designate a double, automatic or self-adjusting packing gland, which is kept tight around the water tube by the action of a spring medium located at the rear of the gland and preferably within the fluid holding vessel or container. This double packing gland operates at the forward end to prevent the escape of the compressed air or motive fluid through the cylinder back cover and at the rear end to preclude the possibility 80 of the water escaping into the cylinder of the machine and insures that the compressed air shall not commingle with the water in its passage from the water holding vessel or container to the bore hole; and 85 also prevents the air from getting into the vessel or container and impeding the flow of water.

In the accompanying drawings a practical embodiment of the invention is illus- 95 trated.

In the drawings—

Figure 1 represents a part longitudinal section of a reciprocating rock drill with the invention applied thereto, and

Fig. 2 is a longitudinal section of the fluid holding vessel or container.

In Fig. 1 of the drawings, 1 denotes the cylinder of the drill or machine, 2 the piston, which is adapted to reciprocate in the 105 cylinder 1, 3 the piston rod, 4 the chuck and 5 the drilling tool or bit. 8 is the axial passage or conduit for the water, which is formed through all of the above-mentioned parts and terminates at the cutting extremity 110

9 of the bit 5. 10 is the cylinder back cover and 11, is the rifle bar of the rotation mechanism, and 12 the rifle nut which is fixed in the rear end of the piston 2 and is engaged by the rifle bar 11 in the well known manner.

13 is the water tube which at its forward end is resiliently secured in the rear end of the bore 8 and at the bottom of the rifle bar 10 bore 14 in the piston 2. 15 is the collar on the tube 13, 16 the counterbore at the rear end of the hole 8, 17, 18, the two rings or buffers of rubber or other suitable resilient material, which are placed around the tube 13 at opposite sides of the collar 15, and are located in the counterbore 16, and 19 is the screwed bush which is screwed into the counterbore 16 and retains the parts 15, 17, 18, in position therein. The cylinder back cover 10 is constructed with a rearwardly extending external screw threaded nipple or projection 20, which serves for attaching thereto the fluid holding vessel or container 21, the latter at its forward end being constructed with an internal screw thread for that purpose.

The projection 20 and back cover 10 are recessed or bored out as indicated at 22, to receive the cylindrical piece or casing 23 which forms the housing for the packings of the self adjusting double gland. The forward end of the casing 23 has a small hole 24 through which the water tube 8 works, and a coincident hole 25 is formed in the back cover for the same purpose. Between the forward end of the casing 23 and the bottom of the recess or bore 22 a packing ring 26 is placed to make a fluid tight joint between the said parts to preclude the escape of the compressed air. Between the other and rear end of the casing 23 and a shoulder or annular surface 27 formed inside the vessel or container a packing ring 28 is positioned to make a fluid tight joint and prevent the escape of water at that point.

The casing 23 is constructed with an external annular recess 29 and with one or, as shown, a plurality of ports or holes 30 leading from said recess into the bore 31 of said part. The projection 20 is also constructed with one or, as shown, a plurality of holes or ports 32 which communicate with the recess 29.

In the forward end of the bore 31 there is arranged a suitable front packing 33 and at the back or rear of said packing 33 a washer 34. In the bore 31 next to the washer 34 there is placed a cylindrical metal piece or member 35 which forms a distance piece between the packing 33 and a similar rear packing 36. The member 35 at its rear end slidingly fits the water supply tube 13 and it is constructed internally to form a recess 37 around the tube. The said member 35 is also

constructed with an external recess 38 and with a suitable number of holes 39 which place the internal recess 37 in communication with the external recess 38. The external recess 38 is in communication with the holes 30 in the casing 21.

As will be readily understood the recess 37, holes 39, and recess 38 in the member 35, and the holes 30 and recess 29 in the casing 23 and the holes 32 in the projection 20 form 75 or provide a free outlet or escape passage for any water that may leak between the tube 13 and the packing 36 and also for any compressed air that may leak between the tube 13 and the packing 33. By this means the possibility of the water entering the cylinder 1 of the drill or of the air commingling with the water in its passage from the vessel or container 21 through the machine to the bore-hole is entirely obviated. 85

In the vessel or container 21 there is arranged a plunger or cylindrical part 40, which at its forward end projects into the bore 31 and engages with the rear end of the rear packing 36. This plunger or part 40 at 90 its rear end slidingly engages in the bore 41 of the vessel or container 21 and is formed with grooves 42 which allow the water to pass freely into the rear portion of the bore 41. The plunger is also reduced between its 95 ends so as not unduly to impede the passage of the water to and through the grooves 42.

In the bore 41 at the rear of the plunger 40 there is located a helical or coiled spring 43 which at its one end engages with the vessel or container 21 at the rear end of the bore 41 and at its other end engages with the back or rear end of the plunger 40. This spring is normally in compression so that it is always acting to force the plunger 40 forward and thereby maintain a 105 continuous pressure between the packings 33 and 36 and the surface of the tube 13.

The bore 41 of the vessel or container 21 constitutes the water holding space or chamber and said vessel or container is constructed with a water inlet 44, so that it can be conveniently connected to the source of water supply. The water supply pipe not shown in the drawings, is preferably a flexible one, and a cock or valve is preferably provided for regulating or controlling the supply of water entering the chamber 41. The connection with the hose pipe may be conveniently screwed into the inlet 44. The 120 inlet 44 may be fitted with a screen for filtering the water as it passes therethrough. 110

The water tube 13 projects through a hole or bore 45 formed through the plunger 40 and extends for a suitable distance into the 125 chamber 41 beyond the rear end of said plunger. The tube 13 is of such a length that its open rear end is always in communication with the chamber 41 during the complete stroke of the piston. 130

The arrangement shown and described is self-adjusting, as the wear of the packings 33 and 36 is automatically taken up by the expansion of the spring 43, with the result 5 that the arrangement does not require attention until the packings are worn out and require to be renewed. The tension of the spring 43 regulates the compression on the gland packings 33, 36, and as the arrangement 10 requires no adjustment once it is assembled and arranged in operative position, it obviates the over-tightening of the gland and the possible damaging of the water-tube by an inexperienced or unskillful operator. 15

What we claim as our invention and desire to protect by Letters Patent is:—

1. In combination, a reciprocating rock-drill having a passage formed through the reciprocated parts, a fluid holding vessel or container attached to the rear end of the drill, a tube attached to and movable with said reciprocated parts, said tube being in communication with the fluid holding vessel 20 or container and with the passage through the reciprocated parts, a self contained detachable double packing gland which is positioned between the end of the rock-drill and the fluid holding vessel or container and 25 operates to prevent the passage of the compressed air or motive fluid into the said vessel or container and also to prevent the passage of the water into the cylinder except through the aforesaid tube, and means 30 for exerting a continuous pressure on the packings to automatically tighten the same around the tube.

2. In combination, a reciprocating rock-drill having a passage formed through the reciprocated parts, a fluid holding vessel or container attached to the rear end of the drill, a tube attached to and movable with said reciprocated parts and in communication with the fluid holding vessel or container 40 and with the passage through the reciprocated parts, a self contained detachable double packing gland which is positioned between the end of the rock-drill and the fluid holding vessel or container and operates 45 to prevent the passage of the compressed air or motive fluid into the said vessel or container.

sel or container and also to prevent the passage of the water into the cylinder except through the aforesaid tube, and means for exerting a continuous pressure on the packings to automatically tighten the same around the tube, said means comprising a plunger which surrounds the tube and is in contact with the rear packing and a spring which is arranged in the vessel or container 55 and engages with said plunger. 60

3. In combination, a reciprocating rock-drill having a passage formed through the reciprocated parts, a fluid holding vessel or container attached to the rear end of the drill, a tube attached to and movable with said reciprocated parts, said tube being in communication with the fluid holding vessel or container, and with the passage through the reciprocated parts, the cylinder back 65 cover being constructed to form a housing for the packing gland surrounding the water tube, an outlet from said housing for the escape of air and water, a casing or member located in said housing, packings between 70 the ends of said casing and the cover and the vessel or container, two packings in said casing and a distance piece between them through which packings and distance piece the water tube works, the distance piece and 75 casing having holes, ports or passages for any compressed air or motive fluid that may escape from the cylinder and any water that may escape from the vessel or container, said holes, ports or passages being 80 in communication with the outlet in the housing, a plunger in the vessel or container engaging with the rear packing and a compression spring in the vessel or container engaging with the rear end of said plunger for 85 maintaining a continuous pressure on the packings around the water tube.

In testimony whereof we have signed our names to this specification in the presence of two subscribing witnesses.
